UNITED STATES PATENT OFFICE.

FRITZ AL. CARLSON, OF KANSAS CITY, KANSAS.

CONVERTIBLE FURNITURE.

1,278,589.

Specification of Letters Patent. Patented Sept. 10, 1918.

Application filed October 25, 1917. Serial No. 198,507.

To all whom it may concern:

Be it known that I, FRITZ AL. CARLSON, a citizen of the United States, residing at Kansas City, in the county of Wyandotte 5 and State of Kansas, have invented certain new and useful Improvements in Convertible Furniture, of which the following is a specification.

This invention relates to convertible furniture, and particularly to convertible swings, having for its primary object to generally simplify and improve the construction and operation of devices of this character as well as to increase their efficiency.

15 A further object of the invention is to provide a convertible swing of the character mentioned which may be very quickly and easily changed from a swing to a bed, and which is equipped with improved means for 20 holding the movable parts of the apparatus in proper position.

A still further object of the invention is to provide a device of the character mentioned which is equipped with changeable 25 seat and bed portions, and with which is associated an improved means for holding the seat portions in proper positions.

Still further objects of the invention reside in providing a convertible swing which 30 shall be of extremely simple and inexpensive construction, which is composed of but few readily assembled parts, all so constructed and arranged as to minimize the opportunity for wear or breakage, which may be very 35 quickly and easily converted from a swing to a bed, and which will prove highly practical and efficient.

With these objects in view, together with others which will appear as the description 40 proceeds, the invention resides in the novel formation, combination, and arrangement of parts, all as will be described more fully hereinafter, illustrated in the drawings, and particularly pointed out in the claims.

45 In the drawings:

Figure 1 is a side elevation of a convertible swing constructed in accordance with the invention, the view illustrating the device as it would appear in being converted 50 into a bed.

Fig. 2 is a top plan view of the device illustrated in Fig. 1.

Fig. 3 is a longitudinal sectional view taken upon line 3—3 of Fig. 2,

Fig. 4 is a bottom plan view of the improved convertible furniture, and

Fig. 5 is a transverse sectional view taken upon line 5—5 of Fig. 2, and illustrating particularly the manner in which the bed and back frames are rotated within their respective supporting frames.

Referring now more particularly to the drawings, 6 indicates a body or supporting frame, comprising in the present instance a pair of relatively short angle bars as shown, 65 from each of which extends upwardly side arm supporting framework 7. This framework may include a pair of upstanding posts 8, supporting at their upper ends an arm rest or shelf 9. The framework also includes 70 a pair of upwardly extending rods 10, firmly secured at their lower ends to the angle bars, and each being provided in its upper end with an eye or loop 11 within which the links of supporting chains 12 are secured. 75 The chains 12 may be secured at their upper ends to rings 13 in a ceiling, and it is obvious that the body or supporting frame thus suspended will be capable of swinging.

The body or supporting frame has revolvably mounted therein a bed frame indicated at 14. This bed frame is of a width substantially equal to the length of the angle bars constituting the supporting frames, and a pivot pin 15 projects outwardly from each end of the bed frame 14 midway of the ends of the frame. The pivot pin 15 at each end of the bed frame is rotatably supported by the adjacent angle bar 6, so that the said bed frame is capable of being rotated upon its 90 longitudinal axis.

In the present instance, the bed frame 14 is of rectangular shape, constituting longitudinal side rails 16, connected at their extremities by the end rails 17; the pivot pins 95 15 being extended through the said end rails intermediate the extremities thereof. One surface of this bed frame is provided with longitudinally disposed slats 18, while the reverse side of the frame is provided with a 100 spring mattress or cushion support 19. A box spring is shown in the drawings, but it will be understood that a woven wire spring may with equal facility be employed. By so constructing the bed frame, either the 105 slatted surface may be presented, or the said frame may be turned so as to present the spring surface.

The means for holding the body and bed frames against relative movement comprises a plurality of slideable locking bolts or bars 21, the said bars being adapted to connect the said frames so as to firmly lock the same against movement. The locking bolts are arranged in pairs at each end of the bed frame and are carried by the latter, and are slidably confined within suitable openings formed in a keeper plate 22. The locking bars are disposed in spaced parallel relation to the longitudinal axis of the bed frame, and are spaced equidistant from the center of the same. The outer ends of the locking bolts pass through the end rails 17 of the bed frame, and are adapted to enter openings provided in the depending portion of the adjacent angle bar of the frame 6. Each of the locking bolts has affixed thereto a collar 23, against which an expansion spring 24 engages, and the said expansion springs seat at their inner ends against the keeper bars 22. This spring arrangement causes the locking bolts 21 to be normally projected, so that when the bed frame is rotated, the extremities of the locking bolts will snap into engagement with the adjacent body frame angle bars. Guide plates 25 may be secured to the angle bars 6 adjacent the openings therein to receive the extremities of the locking bolts, so that the locking bolt ends will be prevented from engaging the upper and lower edges of the body frame bar when the bed frame is rotated.

Pivoted intermediate their ends as at 26 at the center of the bed frame 14 are a pair of levers 27. These levers are of equal length and each has connected to its opposite ends the inner extremity of one of the locking bolts 21. It will be observed that the ends of the levers are connected to locking bolts upon opposite ends of the bed frame, and it is therefore apparent that rocking movement of the lever will cause the said bolts to be withdrawn or projected according to the direction of movement of the said lever.

Slidably arranged in suitable keepers 28 upon the bed frame 14, at the sides of the latter, and intermediate the ends thereof, are operating rods 29 for controlling the locking mechanism. These rods terminate at their outer ends close to the outer edges of the bed frame 14, and may be provided with hand grips 30 as shown. The inner ends of the rods 29 are each connected to the adjacent ends of outwardly diverging links 31, the latter being provided adjacent their outer ends with elongated slots 32, through which pins 33 secured near the outer ends of the levers 27 extend. By this particular construction, it will be obvious that outward pull delivered to either of the lock actuating rods 29 will cause the adjacent ends of the links 31 to move outwardly, and this movement of the links will cause the levers 27 to

rock toward each other. This rocking movement of the levers causes the locking bars 21 to be withdrawn from within the apertures in the body frame, whereupon the said frame may be rotated. Upon release of the operating rods 29, the springs 24 will cause the locking bar to move outwardly, whereupon the controlling apparatus for the actuating rods or bars assumes normal position.

Associated with the main body or supporting frame is a back frame indicated generally at 35, and which is of equal dimensions with the said body frame. The back frame may also be identical in construction with the body frame, excepting that the arm supports and uprights at the extremities of the main frame are eliminated in the back frame. The back frame is hinged as at 36 to the body frame, so as to be capable of swinging from horizontal to vertical position, as indicated by dotted lines in Fig. 1 of the drawings. This back frame is also equipped with a bed frame 14, which is constructed and arranged exactly the same as the bed frame 14 upon the body frame and which is also equipped with holding or locking mechanism the same as that described in connection with the bed frame 14 upon the main supporting frame. The hinged back frame 35 has secured at its outer ends the lower extremities of supporting chains 37, the said chains being adapted to support the back when the latter is either disposed in horizontal or vertical positions.

To support the back 35 in upright position independently of the chains 37, and in such manner as to form a comfortable back rest for the user of the swing, an improved mechanism is provided. This mechanism consists in a pair of reciprocable locking or supporting bars 38, one being arranged upon the arm rests at each end of the body frame. These bars extend laterally of the body frame, and each is connected at its forward end to a relatively small helical spring 39. The spring 39 is confined within a larger helical spring 40, and both springs are secured as at 41 to the foremost of the posts 8 of the arm rests. The rear end of each of the rods 38 extends loosely through the rear-most upright 8 of the arm rest, and is provided with an eye or loop 42. The loops 42 are adapted to receive hooks 43 secured to the end bars of the frame 35. The hooks 43 are pivoted as at 44 as shown, so that the same may be readily detached from engagement with the loops when required.

Assuming the main or supporting frame to be properly suspended from a ceiling, should it be desired to use the apparatus as a porch swing, the back frame 35 is rocked upon its hinges 36 until the hooks 43 snap into engagement within the loops 42 at the rear ends of the rods 38. The revoluble frames in the back frame and body frame

are rotated so as to present their slatted surfaces upward, and, if desired, cushions may be placed upon the back frame and body frame. The locking mechanism for the revoluble frames will hold the latter firmly against rotating, and the hooks 43 engaged in the eyes 42 will hold the said frame in proper upright position. The compound springs 39-40 yield slightly to pressure delivered to the back frame, so that a resilient support for the said back frame is provided. When pressure is applied to the hinged back frame, the smaller helical springs 39 will be expanded, and excessive pressure upon the said back will be borne both by the smaller and larger springs 39-40. When it is desired to use the furniture as a bed, the back frame is released and allowed to assume the position shown in full lines in Fig. 1. The chain 37 will hold the outer end of the frame 35 against passing below the horizontal plane of the main or supporting frame. The latch or locking mechanism for the revoluble frames will then be released, whereupon the said revoluble frames may be rotated; the spring covered sides of the said frames being presented upwardly. Mattresses may then be placed upon the back frame, and the bed is ready for use.

From the foregoing it is obvious that I have provided a convertible swing which is of extremely simple construction and which may be manufactured at low cost. The device is also featured by the lack of intricate or complicated mechanism, and such movable parts as are employed are so constructed and arranged as to lessen the liability for wear or breakage. Should it be desired, suitable means may be employed for enabling the swinging back frame to be held in various angular positions thus rendering the device adaptable to various positions.

While the present is a disclosure of the preferred embodiment of the invention, it is to be understood that the invention is not limited thereto, as various changes in the minor details of construction, proportion, and arrangement may be resorted to if de-

sired without departing from the spirit of 50 the invention as defined by the appended claims.

I claim:—

1. In a convertible swing, a body frame, a bed frame rotatably mounted in said body frame, a pair of locking bars slidably arranged at each end of said bed frame and being spaced equidistant from the pivot of the latter, a pair of levers pivoted intermediate their ends centrally of said bed frame, the ends of said levers being connected one to each of said locking bars, the body frame being provided with catches to receive the ends of said locking bars, springs for normally holding said bars projected, and a rod 65 for moving said levers simultaneously.

2. In a convertible swing, a body frame, a bed frame rotatably mounted in said body frame, a pair of locking bars slidably arranged at each end of said bed frame and being spaced equidistant from the pivot of the latter, a pair of levers pivoted intermediate their ends centrally of said bed frame, the ends of said levers being connected one to each of said locking bars, the 75 body frame being provided with catches to receive the ends of said locking bars, springs for normally holding said bars projected, a reciprocable rod on said bed frame, and links connecting said rod with the said 80 lever.

3. In a convertible swing, a body frame, a bed frame rotatably mounted in said body frame, a pair of levers pivoted intermediate 85 their ends in crossed relation upon said bed frame, a pair of locking bars at each end of said bed frame, each of said levers being connected at one end to a locking bar at one end of said bed frame and at its opposite end to a locking bar at the other end of the 90 frame, and means for moving said levers simultaneously.

In testimony whereof I affix my signature in presence of two witnesses.

FRITZ AL. CARLSON.
